[57] CLAIM

The ornamental design for the combined drinking glass and bottle, as shown and described.

DESCRIPTION

FIG. 1 is a top perspective view of a combined drinking glass and bottle showing my new design;

FIG. 2 is a side elevational view thereof, the undisclosed sides are identical thereto;

FIG. 3 is a top perspective view of a modification of my new design; and,

FIG. 4 is a side elevational view of FIG. 3, the undisclosed sides are identical thereto.

Both the drinking glass and bottle are circular in horizontal cross section.

*Fig. 1**Fig. 2*

*Fig. 3**Fig. 4*
